CLAIM

The ornamental design for an ink cartridge, as shown and described.

DESCRIPTION

FIG. 1 is a front, top, and left side perspective view of an ink cartridge.

FIG. 2 is a rear, bottom, and right side perspective view of the ink cartridge of FIG. 1.

FIG. 3 is a rear, top, and right side perspective view of the ink cartridge of FIG. 1.

FIG. 4 is a rear, top, and left side perspective view of the ink cartridge of FIG. 1.

FIG. 5 is a left side view of the ink cartridge of FIG. 1.

FIG. 6 is a right side view of the ink cartridge of FIG. 1.

FIG. 7 is a top view of the ink cartridge of FIG. 1.

FIG. 8 is a bottom view of the ink cartridge of FIG. 1.

FIG. 9 is a front view of the ink cartridge of FIG. 1; and, FIG. 10 is a rear view of the ink cartridge of FIG. 1.

The broken lines of the FIGURES are for illustration only. The broken lines and the unshaded regions bounded by broken lines form no part of the claimed design.

Line shading is not surface ornamentation.

The dash-dot lines indicate boundaries of the claimed design, and form no part thereof.

1 Claim, 10 Drawing Sheets
